UNITED STATES PATENT OFFICE.

WILLIAM ROSSEM BALL, OF BRYAN, TEXAS.

TOOL OF THE PLIERS TYPE.

971,582.

Specification of Letters Patent. Patented Oct. 4, 1910.

Application filed March 19, 1910. Serial No. 550,432.

To all whom it may concern:

Be it known that I, WILLIAM R. BALL, a citizen of the United States, residing at Bryan, in the county of Brazos and State of Texas, have invented certain new and useful Improvements in Tools of the Pliers Type, of which the following is a specification, reference being had to the accompanying drawings.

10 My invention relates to improvements in tools of the plier type.

The object of the invention is to provide a tool of the plier type having an improved form of handle adapted to be also used for 15 securing the pivoted levers in adjusted position with respect to each other.

With the above and other objects in view, the invention consists of the novel construction, combination and arrangement of parts, 20 hereinafter fully described and claimed, and illustrated in the accompanying drawings in which:—

Figure 1 is a plan view of a tool constructed in accordance with my invention; 25 Fig. 2 is an edge view of the same; and Figs. 3 and 4 are sectional views taken respectively on the planes indicated by the lines 3—3 and 4—4 in Fig. 1.

The invention comprises a pair of crossed 30 levers 1 which are fulcrumed at their points of intersection and adjacent one end by a transverse bolt or pivot 2, the latter passing through registering openings formed in engaged circular recessed portions of the two 35 levers. The short ends 3 of the levers serve as jaws and their opposing inner faces are preferably curved longitudinally and roughened or serrated, as shown at 4, to effectively engage a pipe, a nut, and bits. The long 40 arms 5 of the two levers have their extremities shaped to provide handles 6 and their intermediate portions are formed with registering transverse openings or slots 7 to receive a cross bar 8. The latter is pivotally 45 mounted in the slot of one lever by a transverse pin 9, the latter passing through the bar at a suitable distance from one of its ends, whereby said end projects laterally from such lever and serves as a handle 10. 50 A set screw or other clamping means 11 is provided in a threaded opening 12 in the opposing lever and adapted to impinge against the intermediate portion of the cross bar to cause said bar to lock the two levers in adjusted position. The cross bar slides freely

through the slot in the lever carrying the set screw and is of such length that one of its ends 13 projects laterally beyond such lever and serves as a handle. It will be seen that the construction described permits 60 the tool to be effectively used as a pipe wrench, a nut or bolt wrench, and a brace for a bit. When used as a nut wrench the nut or bolt head is disposed between the jaws 3, the handle ends 6 of the levers are pressed 65 together, and the set screw 11 is tightened to lock the levers in adjusted position and on the nut or bolt. When thus applied the ends or handles 10, 13, of the cross bar may be grasped to turn the tool to rotate the nut or 70 bolt. When the tool is used as a bit brace the flat faced end of the shank or stem of the bit is placed between the opposing inner faces approximately midway between the ends of the levers 5, which faces are preferably serrated or roughened as shown at 14, the set screw then tightened and the tool turned or rotated by grasping the cross bar or the levers. The serrated faces 14 on the levers may be also used for clamping wire 80 and other objects.

Arranged on the inner portions of the jaws 3 of the levers are oppositely disposed tapered staple engaging hooks provided for the purpose of enabling the tool to be used 85 as a staple puller. These hooks are designated by the numeral 16. The device may be used as a wire stretcher and splicer by arranging the wire between the serrated portions 14 of the two levers and then turning 90 and manipulating the device as will be readily understood.

In order to permit the tool to be used for cutting wire and pulling staples, notches 20 are formed in the edges of the circular pivot 95 portions of the two levers as shown.

Having thus described the invention, what is claimed is:

The herein described tool comprising a pair of crossed pivotally connected levers 100 having short ends forming opposing jaws, and long straight ends, the outer extremities of the long ends being shaped to provide handles, and the intermediate portions of said long ends being formed with transverse 105 rectangular openings, one of the latter being elongated, a rectangular cross bar having its intermediate portion arranged in said openings, and its end portions shaped to provide longitudinally extending handles, a pivot 110

pin passed through one of said levers, and said cross bar at a point adjacent to one of the handle ends of said cross bar, whereby the latter is pivotally mounted in said lever 5 with one of its handle ends projecting from said lever, and a set screw arranged in the other lever to impinge against the intermediate portion of the cross bar to adjustably secure said lever to the cross bar and the two

levers in adjusted position with respect to 10 each other.

In testimony whereof I hereunto affix my signature in the presence of two witnesses.

WILLIAM ROSSEM BALL.
